(57) **CLAIM**

The ornamental design for a frameless toggle switch and dimmer wheel, as shown and described.

DESCRIPTION

FIG. 1 is a front perspective view illustrating the frameless toggle switch and serrated dimmer wheel depicted in the

context of its environment by claiming a surface of a cover plate adjacent to the frameless toggle switch and serrated dimmer wheel, with broken lines showing the remaining portion of the cover plate and cover screws for illustrative purposes only;

FIG. 2 is a front view of the frameless toggle switch and dimmer wheel embodiment depicted in FIG. 1, the frameless toggle switch and serrated dimmer wheel depicted in the context of its environment by claiming a surface of a cover plate adjacent to the frameless toggle switch and serrated dimmer wheel, with broken lines showing the remaining portion of the cover plate and cover screws for illustrative purposes only;

FIG. 3 is a left side view of the frameless toggle switch and dimmer wheel depicted in FIG. 1;

FIG. 4 is a right side view of the frameless toggle switch and dimmer wheel depicted in FIG. 1;

FIG. 5 is a top view of the frameless toggle switch and dimmer wheel depicted in FIG. 1;

FIG. 6 is a bottom view of the frameless toggle switch and dimmer wheel depicted in FIG. 1;

FIG. 7 is a front perspective view of a second embodiment illustrating the frameless toggle switch and serrated wheels on either side of the toggle switch depicted in the context of its environment by claiming a surface of a cover plate adjacent to the frameless toggle switch and serrated dimmer wheels, with broken lines showing the remaining portion of the cover plate and cover screws for illustrative purposes only;

FIG. 8 is a front perspective view of the third embodiment illustrating the frameless toggle switch and serrated dimmer wheel, the serrated dimmer wheel having an indicia design, the frameless toggle switch and serrated dimmer wheel being depicted in the context of its environment by claiming a surface of a cover plate adjacent to the frameless toggle switch and serrated dimmer wheel, with broken lines showing the remaining portion of the cover plate and cover screws for illustrative purposes only; and,

FIG. 9 is a detail view of the serrated dimmer wheel and the indicia design that is depicted in FIG. 8.

As noted in the specification above, the cover screws and portions of the cover plate are shown with broken lines for the purpose of illustrating environmental structure and forms no part of the claimed design.
